CLAIM

We claim the ornamental design for a box for package, as shown and described.

DESCRIPTION

The patent or application file contains at least one drawing executed in color. Copies of this patent or patent application publication with color drawing(s) will be provided by the Office upon request and payment of the necessary fee.

FIG. 1 is a plan view in an unfolded state; and,

FIG. 2 is a top perspective view in a folded state of use. The box for package is made of paper and designed as an unfolded item. It is used for packages of alcohol swabs.

1 Claim, 2 Drawing Sheets

(2 of 2 Drawing Sheet(s) Filed in Color)
